(57) **CLAIM**

The ornamental design for a “reader and writer for IC card,” as shown and described.

DESCRIPTION

FIG. 1 is a top, front and left side perspective view of a reader and writer for IC card according to our design;

FIG. 2 is a front elevational view thereof;

FIG. 3 is a rear elevational view thereof;

FIG. 4 is a top plan view thereof, the bottom plan view being a mirror image thereof; and,

FIG. 5 is a right side elevational view thereof, the left side being a mirror image thereof.
